(57) **CLAIM**

The ornamental design for an electric actuator, as shown and described.

DESCRIPTION

FIG. 1 is a front, top and left side perspective view of an electric actuator showing a first embodiment of our new design;

FIG. 33 is a front, top and left side perspective view of an electric actuator showing a fifth embodiment of our new design;

FIG. 34 is a rear, bottom and right side perspective view of FIG. 33;

FIG. 35 is a front view of FIG. 33;

FIG. 36 is a rear view of FIG. 33;

FIG. 37 is a top plan view of FIG. 33;

FIG. 38 is a bottom plan view of FIG. 33;

FIG. 39 is a left side view of FIG. 33;

FIG. 40 is a right side view of FIG. 33;

FIG. 41 is a front, top and left side perspective view of an electric actuator showing a sixth embodiment of our new design;

FIG. 42 is a rear, bottom and right side perspective view of FIG. 41;

FIG. 43 is a front view of FIG. 41;

FIG. 44 is a rear view of FIG. 41;

FIG. 45 is a top plan view of FIG. 41;

FIG. 46 is a bottom plan view of FIG. 41;

FIG. 47 is a left side view of FIG. 41; and,

FIG. 48 is a right side view of FIG. 41.

The broken lines depict portions of the electric actuator that form no part of the claimed design.
